SIGNALING SYSTEM

Milton L. Almquist, Maplewood, N. J., and Albert C. Thompson, New York, N. Y., assignors to American Telephone and Telegraph Company, a corporation of New York

Application August 29, 1933, Serial No. 687,368

4 Claims. (Cl. 179—43)

This invention relates to telephone systems and, more particularly, to improvements in the signaling arrangements of such systems.

In the telephone plant it is common practice to pass ringing and supervisory signals over circuits provided and connected with the local plant by means of direct current channels derived from the talking circuits or pairs. Such channels have particular advantages in that they are independent of the speech channels and accordingly permit signaling operations to be carried on regardless of whether the circuit is in use for speech transmission or not. These channels have the additional advantage that they may be operated on what may be termed a "continuous" basis as compared with channels which are operated on a "spurt" basis, that is, their operation is such that a signaling device may be operated at the distant end of a circuit by the application of signaling current at the local end and this signal will be held operated as long as the signaling current is applied and will be released when the signaling current is removed. In the "spurt" system the signal at the distant point is operated by a spurt of signaling current sent over the line and the signal is locked in by auxiliary control arrangements and released by another spurt of signaling current sent over the line.

In the toll plant it has not heretofore been practicable to obtain the advantages of direct current or other independent signaling channels except in certain special cases, due to the fact that the available direct current channels have generally been used for telegraph purposes and because the cost of other independent channels has ordinarily been prohibitive. Even when direct current channels are available, their use for signaling purposes is limited, except for the shorter circuits, because of cost and performance considerations. It is the principal object of this invention to provide means for obtaining substantially the same results with voice-frequency signaling channels as are obtainable with direct current or other independent signaling channels.

Other objects and features of the invention will appear more fully from the detailed description thereof hereinafter given, when read together with the accompanying drawings in Figures 1 and 2 of which the invention is illustrated. Figs. 1 and 2 when placed side by side, with Fig. 1 on the left and Fig. 2 on the right, constitute a circuit diagram embodying a preferred form of the invention.

In the Figs. 1 and 2 of the drawings, when placed side by side, are shown two stations inter-

connected by a toll line L. Voice-frequency signal receiving apparatus 1 and 6, both of which may be of the same type and well known in the art, and voice-frequency signal sending apparatus consisting of the generators G_x and G_y and the sending relays S and S' are provided at the stations of Fig. 1 and Fig. 2, respectively. In addition, there are also included the cut-off relays CO and CO' which serve to open the talking circuits to the switchboards, the circuits of which are shown in the figures for purposes of illustration. These relays prevent the signaling currents from reaching the subscribers.

In conjunction with the voice frequency equipment enumerated above, the signaling relay arrangements 2 and 7 are provided as part of the signaling apparatus at the stations of Figs. 1 and 2, respectively, and these arrangements serve to translate the signals passed over the line L by the voice-frequency equipment in such a way that the action of the complete signaling channels from the "Out" signaling lead at one station, for example, lead 101 of Fig. 1, to the "In" signaling lead at the other station, for example, lead 102' of Fig. 2, is substantially the same as though the signals had been passed over direct current channels or other independent channels between the two stations. In order to properly control the relays in these arrangements, it is necessary to include the additional "Out" and "In" leads 103, 104, 103' and 104' designated in the drawings as "auxiliary control leads", which are employed for the control of the signaling relay apparatus 2 and 7 involved in the transmission of signals over the line L and over the "signaling" "Out" and "In" leads 101, 102, 101' and 102', as will be described hereinafter.

Before giving a detailed description of the operation of the arrangements of the invention, the various functions that the signaling arrangements of the invention perform will be briefly described. These functions are as follows: When the operator at the station of Fig. 1 makes a connection with the telephone line extending to the station of Fig. 2, the signaling system will cause a signal lamp to light at the switchboard at the station of Fig. 2. The operator at the station of Fig. 2 will then answer and get instructions for the completion of the call from the operator at the station of Fig. 1, and when the operator at the station of Fig. 2 establishes the connection to the toll switching trunk to the subscriber's local office, the signal lamp at the station of Fig. 2 will go out. When the operator in the subscriber's local office of Fig. 2 completes the con-

nection to the called line, the signaling system on the toll line functions to cause a supervisory lamp at the station of Fig. 1 to light to indicate the progress of the call to the operator at that point and when the subscriber answers, the signaling system causes this light to be extinguished. When the subscriber at the station of Fig. 2 hangs up his receiver on the completion of the call, the signaling system causes the lamp at the station of Fig. 1 to light again as a disconnect signal, and when the operator at the station of Fig. 1 takes down the connection, this lamp is extinguished and the signaling system causes the lamp at the station of Fig. 2 to light as a disconnect signal for the operator at the station of Fig. 2. When the operator at Fig. 2 disconnects, the lamp goes out and the circuit restores to normal. At the same time a disconnect signal is also given to the operator in the subscriber's local office at Fig. 2. The signals which have been transmitted thus far may be termed plain "On" and "Off" signals, as they cause the signal lamps to light steadily or to go out and remain out. The signaling system is also capable of transmitting signals of an intermittent nature, which will cause the signal lamps to flash. Such intermittent signals may be caused by one of the operators at Fig. 2 making connection with a busy-back jack, due to all the trunks being busy, or to the called subscriber's circuit being in use, or by the subscriber at Fig. 2 actuating his switchhook in order to signal the operator at Fig. 1. They may also be caused by the operator at Fig. 1 ringing the operator at Fig. 2, in order to recall her after she has cut out of the connection.

The operation of the arrangements of the invention will now be described in detail. When the circuit is idle, voice-frequency signaling currents are transmitted over the line L in each direction. These currents will preferably be of the form now used in telephone practice, that is, a voice-frequency carrier interrupted at a low-frequency rate, but they may be of other forms if desired, provided the resulting signaling system has substantially the same characteristics as regards freedom from interference due to speech currents, tones, noise, etc., as the present system. For purposes of illustration it will be assumed that a current of 1400 cycles interrupted at a 30 cycle rate will be transmitted from Fig. 1 to Fig. 2 and a current of 1000 cycles interrupted at a 30 cycle rate will be transmitted from Fig. 2 to Fig. 1. The 1400-30 cycle current is supplied by the source G_x and is connected to the line through the contacts of relay S, which is held normally operated by ground supplied over leads 4 and 33 and the contacts of relays D and E. Similarly, the 1000-30 cycle current from source G_y in Fig. 2 is connected to the line through contacts of relay S', which is held normally operated by ground supplied over leads 9 and 21 and the contacts of relays D' and E'. The cut-off relay CO in Fig. 1 is held operated by ground supplied to lead 5 from either lead 5_a or lead 5_b. The ground on lead 5_a is obtained through the contacts on relay S, as shown, while the ground on lead 5_b is obtained through the contacts on relay A, lead 32 and the contacts on relay F. The cut-off relay CO' in Fig. 2 is also held operated by ground similarly supplied over leads 10, 10_a, 10_b and 29, and the contacts on relays S', A', and F'. These cut-off relays serve to keep the signaling currents which are transmitted over

the toll line L from reaching the switchboards, and hence from the subscribers.

At the station of Fig. 1, the incoming signaling currents pass over leads 36 to the receiving circuit 1, where, after being amplified and detected by the vacuum tubes 11 and 12, respectively, they cause the polar relay 13 to vibrate in accordance with the 30 cycle interruptions of the signaling current. The operation of relay 13 in conjunction with the tuned circuit 15 and relay 14 causes relay 14 to operate and remain operated steadily for the duration of the incoming signal in a manner well known in the art. The contacts of relay 14 supply ground over lead 3 to hold relay A of circuit 2 operated, the effect of which will be explained subsequently in connection with the description of the relay circuit 2. The tuned circuit 16 in the input of the receiving circuit 1 is provided so that the receiving circuit may discriminate between the voice-frequency currents which are being transmitted from Fig. 1 to Fig. 2 and vice-versa. This circuit is adjusted to be anti-resonant at the incoming signaling frequency of 1000 cycles and resonant at the sending frequency of 1400 cycles, which permits the 1000-25 cycle signaling voltage to reach the grid of the amplifier tube 11, and hence operate the receiving circuit, as previously described, but prevents the 1400-cycle signaling voltage from reaching the tube and operating the receiving circuit. 30

The receiving circuit 6 of Fig. 2 is similar in detail to receiving circuit 1 of Fig. 1 except that the tuned circuit in the input of receiving circuit 6 corresponding to the tuned circuit 16 in receiving circuit 1 is arranged to be anti-resonant at 1400 cycles and resonant at 1000 cycles, since the incoming and outgoing signaling frequencies are reversed at Fig. 2 as compared with those at Fig. 1. When signaling current is received from Fig. 1, the receiving circuit functions in a 40 manner similar to that described above for circuit 1 and causes ground to be applied to lead 8. 35

From the above it will be seen that as long as signaling current is applied to the line at Fig. 1, ground will be present on lead 8 in Fig. 2, and that as long as signaling current is supplied to the line at Fig. 2, ground will be present on lead 3 of Fig. 1. Removal of the signaling current at either end will accordingly cause an indication to be given at the other end by the ground being removed from lead 3 or lead 8 as the case may be. Conversely, applying the signaling current at either end will also produce an indication at the distant end by causing the application of ground to lead 3 or lead 8, as the case may be. 50 These voice frequency channels are controlled by the relay circuits 2 and 7 of Figs. 1 and 2, respectively, in a manner which is hereinafter described.

When a call is originated by the operator at the station of Fig. 1, ground will be placed on the "Out" signaling lead 101 and the "Out" auxiliary control lead 103 by the switchboard circuit of Fig. 1 in a manner to be hereinafter described. The ground on the "Out" signaling lead 101 causes the operation of relay E, which removes the ground applied to lead 4 through the back contact of said relay, lead 33, and the back contact of relay D. This makes relay S release and remove the 1400-30 cycle current from the line by opening the connections to the generator G_x . The release of relay S also removes ground from the cut-off relay CO over leads 5_a and 5, but this does not cause the release of relay CO since ground is still applied to it from relay A through 75

lead 32, the back contact of relay F, and leads 5b and 5.

The removal of the 1400-30 cycle signaling current from the line causes the signal receiving circuit 6 of Fig. 2 to remove ground from lead 8, as hereinbefore described. This causes the release of relay A' which connects ground through lead 24 and the back contact of relay B' to the "In" signaling lead 102'. This ground causes a signal to be brought in at the switchboard of Fig. 2 by means hereinafter described. It will thus be seen that grounding the "Out" signaling lead 101 of Fig. 1 will cause ground to be applied to the "In" signaling lead 102' of Fig. 2. It will be evident later from the description of the disconnect signals that removing the ground from lead 101 will cause the ground to be removed from lead 102', so that the action of the signaling channel from the "Out" signaling lead of Fig. 1 to the "In" signaling lead of Fig. 2 is therefore essentially the same as it would be if a direct current or other independent signaling channel were used between these leads. Obviously an interrupted ground on lead 101 will produce an interrupted ground on lead 102'. When relay A' is released, ground is also applied to the lower terminal of the winding of relay C' over lead 25, thus operating relay C'. In addition, the ground being applied through lead 29, the back contact of relay F' and over leads 10a and 10 to the winding of the cut-off relay CO', is removed. Relay CO' does not release at this time, however, since it is still supplied with ground from relay S' over leads 10a and 10. The operation of relay C' connects ground to the winding of relay F' over lead 28, thus operating relay F'. Relay F' transfers lead 29 from its connection with lead 10b to a connection with lead 31 and the winding of relay G', thus preparing a path for operating relay G' when relay A' re-operates.

The ground on the "Out" auxiliary control lead 103 of Fig. 1 causes the operation of relay B, which prepares a locking path for itself over lead 17, transfers the "In" signaling lead 102 from its connection with lead 26 to a connection with lead 18 in preparation for the reception of supervisory signals which will be transmitted from Fig. 2 in a manner to be hereinafter described, and connects ground to lead 19 to prepare a locking circuit for relay C.

When the operator at the station of Fig. 2 answers, the switchboard circuit causes ground to be placed on the "In" auxiliary control lead 104', which ground causes relay D' to operate and remove the ground it was applying over lead 21 to lead 9 and the winding of relay S'. This causes relay S' to release and remove the 1000-30 cycle current from the line by disconnecting the source Gy. With relay S' released, ground is no longer supplied to relay CO' over lead 10a and 10, and since ground has already been removed from lead 10b, as previously described, relay CO' releases and connects the line through to the switchboard. Relay D', in addition to its above mentioned function, provides a holding path for relay F' by applying ground to lead 28.

The removal of the 1000-30 cycle current from the line causes the voice-frequency receiving circuit 1 of Fig. 1 to remove ground from lead 3, as hereinbefore described. This causes relay A to release and apply ground over lead 21 to the winding of relay C, which operates and locks up over lead 19 to ground supplied through a front contact on relay B, while relay B locks up to ground

supplied over lead 17 from a back contact of relay A. This locking up of relay C through the contacts of relay B is required to prevent relay C from releasing when relay A is subsequently operated and released, as hereinafter explained, in connection with the transmission of supervisory signals from Fig. 2 to Fig. 1. The locking path for relay B is necessary to prevent a false signal being given to the inward operator at Fig. 1 in case the outward operator at that point should disconnect, through error, while the subscribers are talking. The operation of the circuit under the latter condition is somewhat different from its normal action and is described in detail hereinafter. The release of relay A also removes ground from leads 32, 5b and 5, thus releasing relay CO and connecting the line through to the switchboard. The circuit is now in the talking condition and the operators may communicate with each other over line L. The operation of relay C applies ground over lead 23 to relay F which operates and transfers lead 32 from its connection with lead 5b to a connection with the winding of relay G over lead 20, thus preparing a path for operating relay G upon the reoperation of relay A. Relay C also prepares a path for bringing in the supervisory signal in the switchboard of Fig. 1 by connecting leads 18 and 22 together, so that when relay A reoperates, it will apply ground over these leads and through contacts on relay B to the "In" signaling lead 102.

The ground placed on the "Out" auxiliary control lead 103 of Fig. 1 and the ground on the "In" auxiliary control lead 104' of Fig. 2 have, in the manner just described, prepared the relay circuits 2 and 1, respectively, for the transmission and reception of the supervisory signals which will be transmitted from Fig. 2 to Fig. 1 in order that the operator at Fig. 1 may follow the progress of the call. These signals are sent as follows:

When the operator at the station of Fig. 2 has ascertained the called number from the operator at the station of Fig. 1, she passes the required information over a toll switching trunk to an operator in a local office, as will be hereinafter explained. When the operator in the local office completes the connection to the called line, the toll switchboard circuits are caused to function and place ground on the "Out" signaling lead 101' of Fig. 2 in a manner to be subsequently explained. This ground causes the operation of relay E'. Ground is present on lead 30 due to relay D' being operated at this time, and when relay E' operates this ground is extended over lead 9 to the winding of relay S'. Relay S' then operates and connects 1000-30 cycle current to the line from the source Gy. Relay S' also connects ground to relay CO' over leads 10a and 10, causing relay CO' to operate and open the connection between the line L and the switchboard.

With the 1000-30 cycle current on the line, the voice-frequency receiving circuit 1 of Fig. 1 operates as hereinbefore described and places ground on lead 3. Ground on this lead causes relay A to operate and apply ground over lead 22, one of the front contacts of relay C, lead 18 and one of the front contacts of relay B to the "In" signaling lead 102. Ground on lead 102 causes the supervisory lamp in the switchboard cord circuit to light, in a manner to be hereinafter described. Relay A also supplies ground over lead 32, the front contact of relay F, and lead 20 to the winding of relay G, which operates and connects ground over leads 5b and 5 to the cut-off relay CO.

This causes relay CO to operate and disconnect the line from the switchboard.

When the called subscriber answers by removing his receiver from the switchhook, the switchboard circuit at Fig. 2, in a manner to be hereinafter described, removes the ground it was supplying to the "out" lead 101' at that point. With ground removed from lead 101', relay E releases and removes the ground being supplied to relay S' over leads 39 and 9, thus causing relay S' to release and remove the 1000-30 cycle current from the line. When relay S' releases, it also removes the ground it was supplying to relay CO' over leads 10a and 10, and relay CO' releases and re-15 connects the line to the switchboard.

The removal of the 1000-30 cycle current from the line causes ground to be removed from lead 3 of Fig. 1, as previously described. This causes relay A to release and remove the ground it was supplying over leads 22 and 18 and contacts on relays B and C to the "In" signaling lead 102. Removing ground from lead 102 causes the supervisory lamp at the switchboard at Fig. 1 to be extinguished, as will be hereinafter explained. 20 The release of relay A also removes the ground being applied over leads 32 and 20 and the front contacts of relay F to the winding of relay G, which releases. When relay G releases, it removes the ground being applied over leads 5b and 30 5 to the winding of relay CO, which releases and reconnects the line to the switchboard. There is a short delay between the release of relay A and the release of relay CO due to the slow release characteristic of relay G. This delay serves no useful purpose at this time, but has been provided to improve the operation of the system when intermittent signals are transmitted in the manner to be hereinafter explained. The circuit is now in the talking condition again and 35 ready for the subscribers to carry on their conversation.

From the above description it may be seen that with certain relays operated in circuits 2 and 7 by virtue of ground being present on the "Out" auxiliary control lead 103 of Fig. 1 and the "In" auxiliary control lead 104' of Fig. 2, the signaling channel from the "Out" signaling lead 101' of Fig. 2 to the "In" signaling lead 102 of Fig. 1 acts substantially as a direct current or other independent channel; that is, grounding lead 101' causes ground to be applied to lead 102 of Fig. 1 and removing the ground from lead 101' causes ground to be removed from lead 102. Obviously, if an intermittent ground is applied to the "Out" 45 signaling lead 101' of Fig. 2, as may occur if either of the operators at the station of Fig. 2 makes a connection to a busy-back jack or if the subscriber operates his switchhook in order to signal the operator at Fig. 1, an intermittent ground will be placed on the "In" signaling lead 102 of Fig. 1.

It may be noted in connection with these intermittent signals that as far as the application of the signals to the line L at Fig. 2 and their reception at Fig. 1 are concerned, the same result will be obtained if an intermittent ground is placed on lead 104' while a steady ground is present on lead 101'. Also, if an intermittent ground is applied to either lead 101' or 104' without a steady ground on the other, an intermittent ground will be applied to lead 102 of Fig. 1, but this ground on lead 102 will be reversed in phase from that on leads 101' or 104', that is when the ground is applied to lead 104', the ground on lead 70 102 will be removed, and when the ground is re-

moved from lead 104', it will be applied to lead 102. The condition of an intermittent ground on lead 104' without ground being present on lead 101' may occur in case the operator at Fig. 2 should desire to flash the operator at Fig. 1 in case of a cut-off at Fig. 2, as hereinafter described.

In connection with the operation of the system on intermittent signals it should also be noted that there is a short time lag between the application of the voice-frequency signals to the receiving circuit 1 and the subsequent operation of relay A and the cut-off relay CO, during which time interval a short spurt of voice-frequency current is being transmitted to the switchboard and hence to the subscriber. This momentary spurt of voice-frequency current is of no particular consequence when steady signals are involved as it only occurs once, but it would be objectionable to have it occur with every impulse when intermittent signals are involved. In order to obviate this condition, the slow-release relay G has been included in the circuit. When relay A operates intermittently in accordance with the intermittent signals being transmitted over the line, it applies ground intermittently to the "In" signaling lead 102 and to relay G. If relay G were of the fast functioning type it would follow the interruptions and cause relay CO to pulse, with the result that spurts of the 1000-30 cycle current would be transmitted to the switchboard as indicated above; but by making relay G sufficiently slow-release to hold over the interruptions, ground is held on the leads 5b and 5 until the conclusion of the intermittent signals and thus relay CO is kept operated during the time the intermittent signals are on the line.

At the conclusion of the call, both parties hang up, and when the called party at Fig. 2 does so, steady ground is placed on the "Out" signaling lead 101'. This causes ground to be connected to the "In" signaling lead 102 at Fig. 1 as hereinbefore described and the supervisory lamp L₂ in the switchboard at Fig. 1 lights steadily as a disconnect signal. The operator at Fig. 1 then pulls down the connection and the switchboard circuit removes ground from the "Out" signaling lead 101 and the "Out" auxiliary control lead 103. With ground removed from lead 101, relay E releases and reconnects ground through its back contacts, lead 33, and the back contacts of relay D to lead 4 and the winding of relay S. Relay S reoperates and reconnects the 1400-30 cycle current to the line. It also supplies ground over leads 5 and 5a to the winding of relay CO which is already operated by ground from relay G over leads 5b and 5.

Immediately upon the removal of ground from lead 103, relay B releases since its holding path over lead 17 is open at the contacts of relay A, which is operated. When relay B releases, it removes the ground being supplied to the "In" signaling lead 102 over leads 18 and 22 and the contacts of relays A and C, and also removes the ground being furnished to relay C over lead 19. This releases relay C which opens its locking path to lead 19, opens the connection between leads 18 and 22, and removes ground from lead 23. Removing the ground from lead 23 causes relay F to release and open the connection between leads 32 and 20, which in turn causes relay G to release. At the same time relay F establishes a connection between leads 32 and 5b, over which ground from relay A is now transmitted to lead 5 and the winding of relay CO. This has no ef- 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960

fect at this time, however, since relay CO is already operated, as previously described. When relay G releases after a time interval determined by its slow release characteristic, it removes the ground being supplied through its contacts to lead 5b, which removal also has no effect at this time. Circuit 2 has now restored to its original condition.

In Fig. 2, the restoration of the 1400-30 cycle current to the line causes ground to be applied to lead 8. This reoperates relay A' which removes the ground being supplied through its contacts to lead 24 and thence through back contacts on relay B' to the "In" signaling lead 102'. Removing the ground from lead 102' causes lamp L₁' at the switchboard at Fig. 2 to light as a disconnect signal, in a manner to be hereinafter explained. When relay A' operates it also applies ground over lead 29, the armature and front contact of relay F' and lead 31 to the winding of relay G', which operates and applies ground to lead 10b and thence via lead 10 to the winding of relay CO'. This ground serves no useful purpose at this time, however, since relay CO' is already operated by ground supplied over leads 10a and 10 from relay S', which is operated. In addition, relay A' removes the ground being applied to relay C' over lead 25, thus causing relay C' to release. On releasing, relay C' removes the ground it was supplying to the winding of relay F' over lead 28, but relay F' does not release because it is held operated by ground applied to lead 28 through the contacts of relay D', which is still operated.

When the operator at Fig. 2 takes down the connection in response to the disconnect signal received from Fig. 1 as indicated above, ground will be removed from the "Out" signaling lead 101' and the "In" auxiliary control lead 104' by the switchboard circuit of Fig. 2. With ground removed from lead 101' relay E' releases and with ground removed from lead 104', relay D' releases. With both of said relays released, ground is supplied through their back contacts and lead 27 to lead 9, instead of over their front contacts and lead 30, and relay S' accordingly remains operated. When relay D' releases, it also removes ground from lead 28 and the winding of relay F', thus permitting relay F' to release. With relay F' released, the ground being supplied from relay A' over leads 29 and 31 to the winding of relay G' is transferred to lead 10b. Relay G' thereupon releases and removes the ground it was supplying to lead 10b. Circuit 7 has now restored to normal.

In case the operator at the station of Fig. 1 should for any reason wish to recall the operator at the station of Fig. 2 (before having disconnected, of course), she may do so by operating a ringing key (not shown) in her cord circuit which will cause an interrupted ground to be connected to lead 101 in place of the steady ground which is normally present on that lead when a connection is up. As hereinbefore indicated, the condition which is placed on lead 101 of Fig. 1 will be repeated on lead 102' of Fig. 2, so that an interrupted ground will be placed on lead 102', which interrupted ground will cause the inward operator's lamp L₁' to flash at Fig. 2, by means hereinafter described. The intermittent ground on lead 102' is caused by the intermittent operation of relay A' in accordance with the intermittent voice-frequency signals received over the line. Relay C' follows the pulsations of relay A', but relay F' does not do so inasmuch as

it is held operated by ground over lead 28 from the contacts of relay D'. Relay G', which is of the slow-release type, serves to keep the cut-off relay CO' operated steadily during the intermittent signals in the same manner as relay G performs the same function at Fig. 1, as hereinbefore described.

As hereinbefore indicated, the operation of the circuit is somewhat different in case the operator at Fig. 1 should erroneously take down the connection before the subscribers were through talking. When this occurs, the disconnect signals will be transmitted as follows: With the circuit in the talking condition relays B, C and F are operated at Fig. 1 and relays D', C' and F' are operated at Fig. 2. When the operator takes down the connection, ground will be removed from the "Out" signaling lead 101 and the "Out" auxiliary control lead 103, as in the normal case. With ground removed from lead 101, relay E will release and connect ground through its back contacts and those of relay D to lead 4 and relay S, which will reoperate and connect the 1400-30 cycle current to the line, as hereinbefore described. Relay S also supplies ground over leads 5 and 5a to relay CO which operates and disconnects the switchboard from the line. Relay B does not release at this time, however, even though ground has been removed from lead 103, inasmuch as it is locked up over the circuit through its contacts, lead 17, and the contacts of relay A to ground. This locking up of relay B is necessary in order to prevent ground from contacts on relay A passing over lead 26 and the contacts of relay B to lead 102, which ground would cause a false signal to be brought in before the inward operator at the station of Fig. 1.

At Fig. 2, the restoration of the 1400-30 cycle current to the line causes ground to be applied to lead 8. This operates relay A' which removes the ground being supplied through its contacts to lead 24 and thence through back contacts on relay B' to the "In" signaling lead 102'. Removing this ground from lead 102' causes the lamp L₁' to light as a disconnect signal at the switchboard of Fig. 2. When relay A' operates it also causes the operation of relays G' and CO' and the release of relay C' in the same manner as for a normal disconnect, as hereinbefore described.

When the operator at station of Fig. 2 disconnects in response to the signal, ground will be removed from the "In" control lead 104' by the operation of the apparatus in the switchboard circuit. This releases relay D', which applies ground from its back contacts over lead 21, the contacts of relay E' which is released in the present case, and lead 9 to the winding of relay S', which operates and connects the 1000-30 cycle current to the line. Relay S' supplies ground through its contacts to lead 10a and thence via lead 10 to relay CO', but this serves no useful purpose at this time since relay CO' is already operated. When relay D' releases, it also removes the ground which was being supplied over lead 28 to the winding of relay F', which releases and transfers lead 29 from its connection with lead 31 to a connection with lead 10b as hereinbefore described. Circuit 7 is now in its normal condition again.

At Fig. 1 the 1000-30 cycle current causes ground to be applied to lead 3, which ground causes relay A to operate. The operation of relay A removes the ground being applied over lead 17 and the contacts of relay B to the winding of relay B, thus permitting relay B to release. At

- the same time relay A removes the ground it was supplying to lead 26, so that when lead 26 is connected to lead 102 upon the release of relay B, ground will still be prevented from reaching lead 5. 102. When relay A operates, it removes the ground being supplied to the winding of relay C over lead 21, and supplies ground over lead 32 and the contacts on relay F to the winding of relay G, which operates and applies ground to lead 5b.
- 10 The release of relay B opens the holding circuit for relay C which then releases and removes ground from the winding of relay F, which also releases. When relay F releases, it permits relay G to release, as hereinbefore described, and the circuit becomes restored to normal without causing a false signal.

In case the operator at the station of Fig. 2 should pull down the connection before the subscribers have hung up, the ground being supplied 20 from the switchboard circuit to the winding of relay D' over lead 104' will be removed and relay D' will release. This causes the operation of relays S' and CO' in a manner hereinbefore described, and 1000-30 cycle current will be applied 25 to the line L. At the same time ground from the contacts of relay A' is still being supplied over leads 24 and 102' to the switchboard circuit, and with the inward cord down, this ground causes the lamp L₁' associated with the cord to light, in a 30 manner to be hereinafter described, thus calling the attention of the operator at the station of Fig. 2 to the fact that she has broken the connection.

At the station of Fig. 1, the 1000-30 cycle current causes the operation of relay A, which applies ground over leads 22, 18, and 102 to the switchboard circuit, in a manner previously described, thus causing the supervisory lamp L₂ to light. Since the calling subscriber has not hung up, the operator at the station of Fig. 1 also knows that there has been a cut-off. If the operator at the station of Fig. 2 knows the called number and reestablishes the connection, relay D' at Fig. 2 will be reoperated, the lamp L₁' at Fig. 2 will be extinguished, the signaling current will be removed from the line L, the relays at Fig. 1 will restore to the condition they normally assume during the talking interval, and the supervisory lamp L₂ at Fig. 1 will be extinguished. If, however, the operator at the station of Fig. 2 does not know the called number, she may flash the operator at Fig. 1 by operating her talking key K' several times, which will operate relay D' intermittently. This will apply the signaling current to the line L intermittently and cause the lamp L₂ at Fig. 1 to flash as hereinbefore described. When the operator at the station of Fig. 1 answers, the operator at the station of Fig. 2 may ascertain the called number and reestablish the connection as above.

A detailed description has heretofore been given of the operation of the arrangements of the invention in Figs. 1 and 2 for the various types of signals applied to the incoming and outgoing signaling and auxiliary control leads. A description will now be given of the operation of the switchboard apparatus of Figs. 1 and 2 to illustrate how these various signals are applied to and from the outgoing and incoming signal and auxiliary control leads.

In Fig. 1 is shown the switchboard apparatus associated with one end of the signaling system, consisting of the apparatus associated with the toll line L, an operator's cord circuit, and the toll office end of a toll switching trunk. Similar

switchboard apparatus for the other end of the system is shown in Fig. 2.

When an operator at the station of Fig. 1 receives word that a connection is desired with the toll line, she will insert the plug P₁ of her cord in the jack J₁. This will operate relay S₁, which in turn will operate relay A₁. The operation of relay A₁ sets the busy signals BS and places ground on the "Out" signaling lead 101. The application of this continued ground to lead 101 will, through the arrangements of the invention, cause ground to be placed on the "In" signaling lead 102' of Fig. 2, in a manner hereinbefore described in detail. The contacts of relay S₁ also place ground upon the "Out" auxiliary control lead 103, which ground serves to condition the signaling apparatus 15 of Fig. 1 for the reception of signals from the station of Fig. 2, as previously described.

To reach the calling subscriber, the operator at the station of Fig. 1 inserts plug P₂ of the cord 20 in jack J₂ of a toll switching trunk and passes the number to the operator in the local office, who establishes the connection. When the subscriber's line is connected to the trunk, relay G₁ will operate and connect the upper winding of relay S₅ in 25 parallel with its lower winding, thus lowering the sleeve resistance to a predetermined value and causing the lamp L₃ associated with the trunk end of the cord to light. When the subscriber answers relay G₁ will release, the sleeve resistance 30 will change back to a higher predetermined value and the lamp L₃ will be extinguished. Obviously, if the subscriber operates his switchhook, the lamp L₃ will flash, and when he hangs up the receiver at the conclusion of the call, the lamp L₃ 35 will light steadily.

The application of ground to the "In" signaling lead 102' will cause the operation of relay C₁' of Fig. 2. This causes the busy signals BS' associated with the line L to be operated and also lights 40 the incoming signal lamp L₁'. The operator at the station of Fig. 2, upon the lighting of lamp L₁', will operate her talking key K' and receive the necessary information regarding the call from the operator at the station of Fig. 1 (by 45 means of a telephone set not shown), and will then insert the inward plug P₃' into the jack J₂' of a toll switching trunk at Fig. 2 and pass the number called to the operator in the local office, after which she releases the talking key. The 50 operation of the talking key applies ground to the "In" auxiliary control lead 104', which ground is necessary for the proper functioning of the signaling system, as previously described. Inserting plug P₃' into jack J₂' will cause the operation of 55 relays S₃' and S₅'. The operation of relay S₅' serves to connect the winding of the supervisory relay G₁' across the switching trunk for purposes to be described hereinafter. The operation of relay S₃' applies ground through its contacts to the 60 "In" auxiliary control lead 104' in order to keep ground on this lead after the talking key K' is released, and operates relay B₁', which extinguishes the lamp L₁' and provides a holding circuit for the busy signals BS' to take the place of the one supplied by relay C₁' which now releases. In addition, relay B₁' applies battery through its contacts to the armature of relay D₁' and transfers the "In" signaling lead 102' to the winding 65 of relay D₁', which operates since there is ground 70 on lead 102'.

When the operator in the local office at the station of Fig. 2 establishes the connection to the subscriber's line, relay G₁' in the toll switching trunk operates and lowers the resistance of the 75

sleeve to a predetermined value. When the resistance of the sleeve becomes lowered, the marginal value relay S_4' in the toll circuit of Fig. 2 operates and connects ground to the "Out" signaling lead $101'$. This will cause a signal to be transmitted from Fig. 2 to Fig. 1 over the arrangements of the invention, as hereinbefore described, and will cause a steady ground to be applied to the "In" signaling lead 102 at Fig. 1.

As has been previously pointed out, relay A_1 at Fig. 1 is already operated. Hence when ground is applied to the "In" signaling lead 102 , relay S_2 will be operated. The operation of relay S_2 connects a resistance in shunt with the winding of relay S_1 and thus reduces the sleeve resistance of jack J_1 to a lower predetermined value, which causes the lamp L_2 associated with the toll end of the outward cord circuit to light. Thus, when a connection is established with the subscriber's line at the station of Fig. 2, the lamp L_2 at Fig. 1 will light.

When the subscriber at the station of Fig. 2 answers, relays G_1' and S_4' at Fig. 2 release. This will remove ground from lead $101'$ at Fig. 2 and remove ground from lead 102 at Fig. 1 and cause lamp L_2 to go out. Obviously, if the subscriber at the station of Fig. 2 operates his switch-hook, the lamp L_2 will flash. Also, if an intermittent ground is applied to lead $101'$ by the busy signal circuits at Fig. 2, the lamp L_2 at Fig. 1 will flash.

When the subscriber at the station of Fig. 2 hangs up, relays G_1' and S_4' reoperate and the lamp L_2 at Fig. 1 will light steadily. If the subscriber at the station of Fig. 1 has also hung up, the lamp L_3 associated with the trunk end of the cord circuit will also light as hereinbefore described. Both lamps being lighted indicate to the operator at the station of Fig. 1 that she should disconnect, which she does by removing plugs P_1 and P_2 from the jacks J_1 and J_2 of the toll line L and the switching trunk, respectively. Removing the plug P_1 from the line jack J_1 , extinguishes lamp L_2 and causes relay S_1 to release, which in turn releases relay A_1 and also removes ground from lead 103 . The release of relay A_1 removes ground from lead 101 , releases the busy signals BS , and transfers lead 102 from its connection to the winding of relay S_2 to a connection with the winding of relay C_1 through the contacts of relay B_1 . Relay S_2 releases, but relay C_1 does not operate at this time because the removal of ground from leads 101 and 103 has caused the ground on lead 102 to be removed, as hereinbefore explained. Removing the plug P_2 from the switching trunk jack J_2 causes the lamp L_3 associated with the trunk end of the cord to go out and releases relays G_1 and S_5 in the trunk, the release of which relays causes a disconnect signal to appear at the local office.

The removal of ground from leads 101 and 103 causes the signaling system to send a signal over the line by the arrangements of the invention and restore itself to normal, as previously described. This signal causes ground to be removed from lead $102'$ at Fig. 2 and causes relay D_1' at Fig. 2 to release and supply battery to light lamp L_1' which will light as a disconnect signal for the operator at the station of Fig. 2. When the operator at the station of Fig. 2 responds to the disconnect signal and removes the plug P_3' from the jack J_2' of the switching trunk, relays S_3' and S_4' in the toll line circuit and relays G_1' and S_5' in the trunk release. With relay S_3' normal, relay B_1' releases and deen-

ergizes the busy signals BS' and removes the battery being supplied through the contacts of relay D_1' to the lamp L_1' , which goes out. When relay S_3' releases, it also removes ground from lead $104'$, while the release of relay S_4' removes ground from lead $101'$. The removal of ground from these leads causes relay circuit 7 to restore to normal as hereinbefore described. The release of relays S_5' and G_1' in the switching trunk causes a disconnect signal to be given to the operator in the local office. When the operators in the local offices at the stations of both Fig. 1 and Fig. 2 have disconnected, the entire circuit will be in its normal condition.

If the outward operator at the station of Fig. 1 wishes to recall the operator at the station of Fig. 2, she does so by operating the ringing key (not shown) in the outward cord circuit. This key applies battery through the tip of plug P_1 to the tip of the line and thence to the winding of relay K_1 , which operates. Relay K_1 removes the steady ground being supplied to lead 101 from relay A_1 and replaces this steady ground by an intermittent ground. This causes the steady ground on lead $102'$ at Fig. 2 to change to an intermittent ground in a manner hereinbefore described. With relay B_1' at station Y operated, as it is when a recall signal is being transmitted, this intermittent ground on lead $102'$ causes relay D_1' to operate intermittently and flash lamp L_1' as an indication to the operator at the station of Fig. 2 that the operator at the station of Fig. 1 wishes to communicate with her.

In case the operator at the station of Fig. 2 should cause a cut-off by taking down the connection while the subscribers are talking, relay S_3' will release and remove ground from lead $104'$. This will cause a signal to be transmitted to Fig. 1, which signal will cause the supervisory lamp L_2 at Fig. 1 to light, as hereinbefore described. When relay S_3' releases, it also releases relay B_1' , which transfers lead $102'$ from the winding of relay D_1' to the winding of relay C_1' . This causes relay D_1' to release, and since ground is present on lead $102'$, relay C_1' operates and causes lamp L_1' to light. In addition, relay C_1' also holds the busy signals BS' operated.

The lighting of lamp L_1' when the cord is down is an indication to the operator at the station of Fig. 2 that she has broken the circuit. If she can reestablish the connection immediately, relay S_3' will be reoperated and will in turn reoperate relay B_1' and apply ground to lead $104'$. The lamp L_2 at Fig. 1 will be extinguished, relay D_1' will be reoperated, and relay C_1' will release and extinguish lamp L_1' and the circuit will be in the talking condition again.

If, however, the operator at the station of Fig. 2 does not know the called number, she may flash the operator at the station of Fig. 1 and obtain it from her, after which she can reestablish the connection as just indicated. Inasmuch as the inward cord is down so that relay S_3' is released, the operator at the station of Fig. 2 may flash the operator at the station of Fig. 1 by operating her talking key intermittently. This will cause an intermittent ground to be placed on lead $104'$, which will cause intermittent signals to be sent over the line L , and as hereinbefore indicated, such intermittent signals will cause the lamp L_2 at Fig. 1 to flash.

Although the invention has been described on the basis of calls being originated at the station of Fig. 1 and received at the station of Fig. 2, the circuits are entirely symmetrical and may

be operated just as readily for calls going in the reverse direction.

While the invention has been disclosed in certain specific arrangements which are deemed desirable, it is understood that it is capable of embodiment in many and other widely varied forms without departing from the spirit and scope of the invention as defined by the appended claims.

What is claimed is:

10. 1. The method of signaling over a telephone circuit which consists in transmitting from one end of said circuit while said circuit is not in use for the transmission of telephone currents, an alternating current of a first frequency, transmitting from the other end of said circuit while said circuit is not in use for the transmission of telephone currents, an alternating current of a second frequency, removing the current of the first frequency from the telephone circuit so that an indication is provided at the distant end when a telephone connection is desired, removing the alternating current of the second frequency to clear the circuit for the telephone connection, reapplying and subsequently removing the alternating current of the second frequency to said circuit at the distant end, indicating at the first end of said circuit the application and removal of said alternating current, and reapplying the alternating current of the first frequency when the circuit is to be restored to its original condition.

2. The combination of a signaling circuit which is capable of transmitting speech currents as well as auxiliary signals, means for simultaneously transmitting auxiliary signals in opposite directions over said signaling circuit while said circuit is not transmitting speech currents, means for removing the auxiliary signaling current transmitted over said signaling circuit in one direction when connection is made to the signaling circuit for the transmission of speech

currents, means responsive to the removal of the latter auxiliary signaling circuit for indicating at the opposite end of the circuit that a connection is for the transmission of speech currents to be made to said circuit, and means for removing the auxiliary signaling current transmitted over the signaling circuit in the reverse direction when said connection is made.

3. The combination of a circuit which is capable of transmitting both speech currents and auxiliary signaling currents, means for simultaneously transmitting alternating current signals of predetermined frequencies in opposite directions over said circuit as auxiliary signaling currents for said circuit while said circuit is not in use for the transmission of speech currents, means for removing said auxiliary signaling currents from said circuit, means for subsequently reapplying said auxiliary signaling currents to said circuit, and means responsive to the removal and reapplication of said auxiliary signaling currents to provide calling and supervisory indications of the condition of said circuit.

4. The combination of a circuit which is capable of transmitting both speech currents and auxiliary alternating currents, means for simultaneously transmitting said auxiliary alternating currents in opposite directions over said circuit while said circuit is not in use for the transmission of speech currents, means for controlling the application and removal of said auxiliary alternating currents, a plurality of calling and supervisory signals for indicating the condition of said circuit and means responsive to the removal and reapplication of said auxiliary alternating currents for operating said calling and supervisory signals.
